(57) **CLAIM**

The ornamental design for a CD holder rack, as shown and described.

DESCRIPTION

FIG. 1 is a perspective view of a CD holder rack showing our new design;

FIG. 2 is a front elevational view thereof;

FIG. 3 is a left side elevational view thereof, with a right side elevational view being a mirror image thereof;

FIG. 4 is a rear elevational view thereof;

FIG. 5 is a top plan view thereof; and,

FIG. 6 is a bottom plan view thereof.

The portions shown in broken lines in FIGS. 1-6 form no part of the claimed design.
